UNITED STATES PATENT OFFICE.

CHARLES J. VELTE, OF WATERBURY, CONNECTICUT.

ATHLETE'S MEDAL.

Application filed December 28, 1922. Serial No. 609,459.

To all whom it may concern:

Be it known that I, CHARLES J. VELTE, a citizen of the United States, and a resident of Waterbury, county of New Haven, 5 and State of Connecticut, have invented certain new and useful Improvements in Athletes' Medals, of which the following is a specification.

This invention relates to athletes' medals, 10 and more particularly to a pendant medal to be used as a watch fob or the like, and adapted to receive detachable panels which may be earned by an athlete for excellence in various sports and activities.

15 One object of the invention is to provide an ornamental athlete's fob or medal provided with a series of perforations to receive panels—each panel indicating the successful performance of some particular test 20 in a sport or activity.

A further object is to provide a constructive medal of the above nature, provided with detachable panels, the grade of achievement in the particular sport being shown by 25 the material of which the panel is made.

30 A further object is to provide an athlete's medal which will serve for a wide range of sports and activities, and which may be used equally well by beginners and by athletes 35 of intermediate and advanced degrees of strength and skill.

35 A further object is to provide a device of the above nature which will be simple, compact, cheap to manufacture, easy to manipulate, and very efficient and durable in use.

With these and other objects in view, there has been illustrated on the accompanying drawing one form in which the invention may be conveniently embodied in 40 practice.

Fig. 1 represents a perspective view of a complete constructive medal embodying the invention, as it appears when used as a watch fob attached to the end of a leather 45 strap.

Fig. 2 is a front view of the medal base, with only one panel in position.

Fig. 3 is a side sectional view of the medal base taken along the line 3—3 of Fig. 2, 50 looking in the direction of the arrows.

Fig. 4 is a perspective view of one of the panels and attaching nuts, shown in separated relation.

Numerous methods have been previously 55 tried out, to stimulate interest in all-round physical development, such as the pentath-

lon, the McCurdy, and the hexathlon tests. However, none of these systems have been very widely used on account of the fact that the tests themselves and the awards given 60 were not sufficiently attractive to appeal to the vast majority of persons making use of athletics for physical upbuilding and recreation.

According to the present invention, the 65 above and other disadvantages have been avoided, and a medal has been provided which will make a universal appeal to the young and old, the weak and the strong, and beginners and experts.

70 Referring now to the drawings in which like reference numerals denote corresponding parts throughout the several views, the numeral 10 indicates a medal base comprising in this instance a disk-shaped watch fob, 75 preferably made of bronze. The medal base 10 is preferably circular in shape except at its top where it is provided with a projecting section 11 having a slot 12 through which a leather strap 13 is adapted to pass. The strap 13 is provided with a tongue 80 buckle 14 for securing its ends together, and is connected at its other end to a watch adapted to be located in the pocket of the 85 wearer.

The medal base 10 is provided with a series of perforations 15—five in number in this instance—uniformly spaced from the periphery thereof. The perforations 15 are 90 preferably equally spaced from one another, and so arranged that the lines joining their centers will form a pentagon, with one of its sides parallel with the strap slot 12 previously mentioned.

95 Each of the perforations 15 comprises a cylindrical front recess 16 of relatively small diameter and length, and a rear recess 17 of considerably greater diameter and length, as compared to the recess 16. A series of panels 18 corresponding to achievements in various lines of sport or activities, are provided, and are adapted to be interchangeably inserted in the perforations 15. The panels 18 are preferably made identical 100 in shape, but with different designs engraved or stamped on the heads thereof. For example, when the device is to be employed as a Y. M. C. A. medal, one of the designs for the panels may show an athlete lifting a weight—representing gymnastics; another design may show a jumper—representing athletics; another design may show 105 110

a runner—representing athletics, while a fourth design may show a swimmer—representing swimming. A fifth design may show an arbitrary symbol representing service, such as working on the leader's corps, or on a team, taking part in exhibitions, ushering, bringing in new members, etc.

Each of the panels comprises a flat circular head portion 18^a having a threaded stud 19 projecting from the rear face thereof. A nut 20 is also provided, and is adapted to be screwed upon the stud 19 for securely holding the panel in position on the medal. The panels may be made of several metals, such as bronze, silver, and gold, representing increasing degrees of excellence in the same sport or activity.

In operation, when an athlete has successfully passed the first test in a particular sport, he will be presented with a panel of bronze having the appropriate design for said sport. He will insert this panel in the proper perforation in the medal base or fob, which may have been given him at the same time, or previously. In attaching a panel to the medal base, the stud 19 will first be inserted through the perforation 15 as far as it will go. The circular face of the head portion 18^a will then lie in contact with the front of the disk 10. The nut 20 will next be screwed upon the stud 19 by means of a suitable wrench or other tool, until it tightly engages the base of the enlarged recess 17.

When the athlete succeeds in passing the next higher test in the same branch of sport, he will be presented with another panel of the same design, but made from a different metal, such as silver. He will then remove the bronze panel and substitute the silver panel therefor in the same perforation. Again, if he passes the next or most advanced test in the same sport, he will be presented with a gold panel of the same design, which will then be substituted for the silver panel.

One advantage of this invention is that the medals may be employed to encourage boys to begin striving for higher accomplishments in various lines of sport at an early age, and to continue their effort as they become able to pass the more advanced tests. The interest of the boys will thus be maintained over the entire period of their growth and development.

A further advantage is that the athlete does not have to wait until he has passed the most advanced tests before receiving an award, but will be presented with a medal base and panel as soon as he has passed the most elementary test in any one particular sport. The possession of a medal base with an incomplete set of panels will stimulate him to strive for a full set of panels, and having a full set of bronze panels, there will

be a strong incentive for him to try for silver and gold panels.

While the invention has been herein illustrated as applied to an athlete's medal, it will be understood that it is not to be limited to such use, but the medal may also be employed with detachable interchangeable panels in various other systems such as in the schools to encourage scholarship, in fraternal orders to indicate the number of degrees obtained, or in the Army and Navy, to indicate various honors achieved, campaigns participated in, etc.

While there has been disclosed in this specification, one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an athlete's medal, a disk having a plurality of perforations, and a plurality of ornamental panels adapted to be detachably secured in said perforations to indicate the achievements of said athlete in various branches of sport or other activities.

2. In an athlete's medal, a fob disk having a slot through which the end of a strap is adapted to pass, said disk having a plurality of symmetrically arranged perforations, and detachable means to be inserted through said perforations to represent the various accomplishments of the athlete.

3. In an athlete's medal, a disk having a plurality of perforations, each of said perforations being enlarged at the rear, and a plurality of ornamental panels adapted to be detachably secured in said perforations to indicate the achievements of an athlete in various branches of sport or activities, said panels having studs adapted to fit within the small ends of said perforations, and means to be located in the enlarged ends of said perforations for securing said panels in position.

4. In a constructive medal, a metal disk, a plurality of perforations in said disk, said disk having a slot to receive a strap to permit the medal to be used as a watch fob or the like, panels adapted to be attached to the face of said disk, said panels having studs extending through said perforations, and means on the rear of said disk to engage said studs to hold said panels in position.

5. In a constructive medal, a circular metal disk, a series of uniformly and symmetrically spaced perforations arranged

equidistant from the center of said medal, panels to be secured to said disk, each panel having a head section and a threaded stud projecting rearwardly therefrom, each of 5 said studs adapted to extend through one of said perforations, and a nut to be threaded on each stud behind said disk to hold said panel firmly in position.

6. In an athlete's medal, a disk having a 10 plurality of perforations, a plurality of panels to be detachably secured to said disk, each of said perforations comprising front cylindrical apertures of small diameter and

depth, and rear cylindrical apertures of larger diameter and depth, each panel consisting of a flat head adapted to lie in contact with the face of said disk and having a stud extending through one of said perforations, said studs fitting said front apertures, and nuts threaded on said studs adapted to 15 fit within the rear enlarged apertures of said perforations.

In testimony whereof, I have affixed my signature to this specification.

CHARLES J. VELTE.
